UNITED STATES PATENT OFFICE.

SIMEON V. SHERWOOD, OF MINNEAPOLIS, MINNESOTA.

SAFETY DEVICE FOR RAILWAY-CARS.

1,142,635.

Specification of Letters Patent. Patented June 8, 1915.

Application filed February 19, 1915. Serial No. 9,422.

To all whom it may concern:

Be it known that I, SIMEON V. SHERWOOD, a citizen of the United States, residing at Minneapolis, in the county of Hennepin and 5 State of Minnesota, have invented new and useful Improvements in Safety Devices for Railway-Cars, of which the following is a specification.

This invention is an improved safety device for use on railway cars, locomotives and other vehicles which operate on railway rails, the object of the invention being to provide an improved device of this character which co-operates with the usual flanged 15 wheels of a railway car to prevent the car wheels from leaving the track.

The invention consists in the construction, combination and arrangement of devices hereinafter described and claimed.

20 In the accompanying drawings, Figure 1 is an inverted plan of a portion of a railway car showing a track provided with safety devices constructed in accordance with my invention. Fig. 2 is an end elevation of the 25 same. Fig. 3 is a vertical longitudinal sectional view of the same. Figs. 4—5 are detail views of one of the safety devices.

For the purposes of this specification the body of a car is indicated at 1 and one of the 30 trucks is indicated at 2 the side members of the truck being indicated at 3, the cross beams at 4, intermediate longitudinal beams at 4^a, the axles at 5 and the usual flanged wheels 6 being provided which bear on the 35 track rails 7.

In accordance with my invention I provide guard wheels 8 which are arranged in an inclined position on the inner sides of the track rails and which are peripherally 40 grooved as at 9 so that each guard wheel is formed with a flange 10 above a track rail and a flange 11 on the inner side of the head thereof. Each guard wheel has trunnions or short axle 12 mounted in the bearings 13 45 in the arms 14 of a bifurcated pedestal 15 which is arranged in an inclined position and preferably at an angle of about 45°, so that the guard wheels are also arranged at such angle. The pedestal is formed at its 50 upper end with a head or plate 16, which is here shown as formed integrally therewith and which is secured to the under side of one of the cross beams 4 of the truck by

means of bolts 17. Strengthening ribs 18 are arranged in the angles between the head 55 16 and the inclined pedestal 15. Each pedestal is also provided with a pair of oppositely extending braces 20 the said braces having their upper ends bolted as at 21 to the lower sides of the intermediate longitudinal beams 4^a of the truck and having their lower ends bolted to the pedestal as at 22. Two of my improved safety devices will 60 preferably be employed on each truck of a railway car, locomotive or the like so that 65 the guard wheels will be arranged on the inner sides of the both track rails.

Having thus described my invention, I claim:

1. A truck for railway cars or the like 70 and comprising side members, cross beams, and intermediate longitudinal beams and also provided with axles and with flanged wheels to bear on the rails of a track, the truck being further provided with inclined 75 guard wheels arranged to bear on the heads and inner sides of the railway tracks and with supports in which said guard wheels are mounted, said supports being secured to one of said cross beams and braces for said 80 supports extending therefrom and secured to the intermediate longitudinal beams.

2. A safety device of a class described comprising an inclined pedestal having its lower portion bifurcated and provided at 85 its upper end with a head adapted to be bolted to the under side of a cross beam of a truck and a guard wheel mounted in the bifurcated portion of the pedestal and extending downwardly therefrom, said guard 90 wheel having an axle mounted in bearings in the arms formed by the bifurcation of the pedestal and having peripheral grooves whereby said guard wheel is formed with an upper flange to bear above a track rail 95 and with a lower flange to bear against the inner side of said head of the rail and braces bolted to said pedestal and adapted to be secured to a member of the truck.

In testimony whereof I affix my signature 100 in presence of two witnesses.

SIMEON V. SHERWOOD.
